UNITED STATES PATENT OFFICE.

GEORGE WATSON FOSTER, OF STROUDSBURG, PENNSYLVANIA.

ENGINE.

Application filed January 16, 1925. Serial No. 2,917.

My present invention has reference to a hydraulic engine.

An object is the provision in a hydraulic engine of a cylinder through which a fluid flows and which has a weighted float piston therein, and means for trapping the water in the cylinder to buoy the piston in its upward stroke, and means for releasing the water to permit the piston to gravitate in its downward stroke, and wherein the reciprocation of the piston is timed and is continuous.

A further object is the provision of a hydraulic engine in which a cylinder having a port establishing a water inlet to the bottom thereof is provided and wherein a valve controls the water outlet at the bottom of the cylinder, said cylinder having a weighted piston movable therein and influenced in its upward stroke by the water in the said cylinder when the valve is closed, and also wherein such movement of the piston will actuate mechanism for opening the valve so that the water will flow out of the cylinder to permit of the descent of the piston on its downward or power stroke, and wherein the parts are so arranged as to insure a free working thereof and proper timed movement of the piston in both directions.

With the above broadly stated objects in view and others which will appear as the nature of the invention is better understood, the invention resides in the combination and arrangement of parts hereinafter described and pointed out with particularity in the appended claims, it being understood that changes in form and proportion falling within the scope of the claims may be resorted to without departing from the principles involved.

In the drawings:—

Figure 1 is a side elevation of a hydraulic engine in accordance with this invention.

Figure 2 is a top plan view thereof.

Figure 3 is a central vertical longitudinal sectional view through the cylinder and the parts associated therewith.

Figure 4 is a front elevation of the mechanism supported on the top of the cylinder.

Figure 5 is a perspective view of one of the latching dogs.

Figure 6 is a sectional view on the line 6—6 of Figure 3.

As disclosed by the drawings I make use of a cylinder 1 having a closed bottom pro-

vided with a tubular extension forming a water outlet 2. The cylinder, on one side thereof, is integrally formed with an outwardly directed lip 3, the top of which being disposed below the top of the cylinder and this lip establishes a water inlet or port to the bottom of the cylinder.

The cylinder may be partly immersed in a body of water, the open top, however, being maintained above the level of such body of water so that the water will flow through the lip into the bottom of the cylinder. The water may have a natural or gravity flow, and such water is designed to be maintained for predetermined intervals in the cylinder through the medium of a slidable valve 4 which is arranged in the outlet 2 and which is of a weight sufficient to be unseated by the weight of the water in the cylinder but which is held closed to retain water in the cylinder in a manner which will presently be set forth.

Received in the cylinder there is a preferably hollow weighted piston 5. In order to reduce friction between the piston and the bore of the cylinder, the piston is preferably provided with peripheral rollers 6 that contact the wall of the cylinder bore. The piston is in the nature of a float and is designed to be influenced in its upward stroke by the pressure of water let into the cylinder when the valve 4 is closed.

On the top of the cylinder, at the end thereof, directly above the outlet pipe 2, I secure a frame comprising side members held in spaced relation by suitable connecting means 8. Between the side members at the top of the frame I journal the shafts or trunnions 9 of a centrally grooved wheel 10. The rims of the wheel are each provided with a peripheral notch 11, the said notches defining inner angle and outer straight walls, and these notches are reversely arranged, that is, the straight shoulders thereof are disposed adjacent to each other. Arranged in the groove of the wheel there are pins or teeth 12 which pass through the links of a chain 13. This chain has one of its leads directed through the cylinder, and passes through a tube 14 in the piston 5 and has its ends secured to the valve 4. The opposite lead of the chain has secured thereon a counter-balancing weight 15. Pivotally secured to the respective side members 7 of the frame there are latching dogs 16 and 17 respectively, the said dogs having

their active ends engageable in the notches 11 on the periphery of a grooved wheel 10 and whereby the said wheel is held from turning under the influence of the weight 15. 5 The dogs 16 and 17 have angle tail portions 18 and 19 respectively which are extended beyond the frame at opposite angles.

The tail portions of the dog project through what I will term the front face of 10 the frame, and this part of the frame has secured thereon upper and lower outstanding bracket plates 20 and 21 respectively, and through suitable openings in these plates there are guided the spaced rods 22 15 and 23 of a slide. The rods 22 and 23 are approximately centrally connected by a brace member 24, and adjustably secured by means 25 on each of the said rods there is a contact or trip member 26 and 27 respectively. These trip members are in the nature of blocks, and surrounding the rod 23 and exerting a pressure between the upper trip member 27 and the bracket plate 20 there is a spring 28. The spring sustains 25 the guide rods normally in open position and the trips 26 and 27 are respectively in the path of engagement with the tail portions 18 and 19 of the latching dogs 16 and 17.

The latching dogs are each preferably 30 journaled on a single shaft 29 which has arranged therearound a coiled spring, the ends of which being connected to the respective dogs and whereby the said dogs have their active or toothed ends forced into 35 contact with the rim portions of the grooved wheel 10.

Secured on the top of the piston float 5 there is a piston rod 30. This rod 30 has 40 adjustably secured thereon by means 31 an upper stop collar 32 and a lower stop collar 33. These collars are arranged between a cross piece 34 that is firmly secured to the respective slide rods 22 and 23.

As previously stated, the flow of water 45 from a stream or other body is directed through the lip into the bottom of the cylinder. This water finds an outlet as long as the valve 4 is in open position. We will, however, suppose the valve to be closed. The 50 force of the volume of water let in the cylinder and acting on the piston float 5 will move the same in an upward direction in the cylinder. The stop element 33 on the piston rod 30 will be thus caused to contact with the cross piece 34 on the rods 22 and 23, moving both of the rods in an upward direction. The trip 26, being in the path of contact with the tail 18 of the latching dog 16 will, when contacting therewith, swing the 55 said dog to releasing position. It is to be understood that the weight of the water in the cylinder will overbalance the counter weight 15, with the result that upon the completion of the up stroke of the piston 60 and the release of the holding means for the 65

grooved wheel 10, the valve 4 will be forced to open position, the weight of the water drawing on the chain to move the counter-balancing weight 15 upwardly. The weighted piston float will then gravitate in 70 a second direction to complete its power stroke. The downward movement of the piston will cause the stop element 32 on the piston rod 30 to contact with the upper face of the cross piece 34, thus influencing the 75 guide rods 22 and 23 in a downward direction and causing the trip 27 to contact with the tail 19 of the second holding dog, releasing this dog so that the counter-balancing weight will gravitate downwardly, 80 drawing on the chain to cause the latter to close the valve 4. These operations are continued as long as water is let into the cylinder. The parts are so constructed and arranged that a smooth and continuous operation 85 of the engine is maintained. The rapidity of the reciprocation of the piston is regulated by adjusting the trips 26 and 27 and likewise by adjusting the stop or contact elements 31 and 33 on the piston rod 90 30, and it is believed that the simplicity of the invention as well as the many advantages thereof will be perfectly apparent to those skilled in the art to which such devices relate.

I have not illustrated a power transmitting mechanism associated with the improvement as disclosed in my present application, as I have in mind a novel mechanism for this purpose which, when perfected, will form the subject matter of another application. It is obvious, however, that the piston rod could be toothed and engage with a toothed wheel which might be held from movement, except upon the downward 105 or power stroke of the piston, while other obvious means for transmitting power should present themselves.

Having described the invention, I 110 claim:—

1. In a hydraulic engine, a cylinder having an open mouth and designed to be partly submerged in a body of flowing water, a lip on one side of the cylinder below the 115 mouth thereof establishing a water inlet to the body of the cylinder, said cylinder having a tubular outlet on the bottom thereof, a slide valve controlling the outlet, a piston movable in the cylinder, a rod therefor, weight influenced flexible means connected to the valve, a grooved wheel over which 120 said means is trained, upper and lower spring influenced dogs engaging the roller for holding the same from turning under the influence of the weighted means, means actuated by the piston rod in the movement of the piston in both directions for alternately releasing the mentioned dogs, and whereby to permit of the weighted means to 125

alternately open and close the valve, for the purpose set forth.

2. A hydraulic engine including a cylinder having a closed bottom provided with a valve controlled opening and which cylinder is designed to have a fluid body flow therethrough, a piston in the cylinder having a rod extension, a frame on the cylinder, spaced connected slidable rods guided on the frame, adjustable contacts on the rod for engaging the frame for moving the same in two directions in accordance with the movement of the rod and piston, trip elements

on the rods, a grooved roller journaled on the frame, spring influenced upper and lower dogs engaging the roller to hold the same from free movement, a weight influenced flexible element trained over the roller and connected with the valve, and upper and lower adjustable trip elements on the respective rods in the path of contact with the respective dogs, as and for the purpose set forth.

In testimony whereof I affix my signature.

GEORGE WATSON FOSTER.
